UNITED STATES PATENT OFFICE.

JOHN N. QUINN, OF CINCINNATI, OHIO.

MACHINE FOR CORRUGATING PAPER.

1,284,771.

Specification of Letters Patent. Patented Nov. 12, 1918.

Application filed March 27, 1916. Serial No. 86,834.

To all whom it may concern:

Be it known that I, JOHN N. QUINN, a citizen of the United States, and residing at Cincinnati, in the county of Hamilton and State of Ohio, have invented a new and useful Improvement in Machines for Corrugating Paper, of which the following specification is a full disclosure.

My invention relates to devices adapted to 10 operate upon a continuously traveling web of paper or paper-board for manufacturing a corrugated, embossed or fluted product, or otherwise appropriately shaping the material as for forming folding packing containers.

An object of the invention is to provide 15 opposing die members traveling as endless carriers, arranged to progressively coöperate, whereby they successively engage a traveling web of material, drawing the same therewith, and in a feeding or traversing direction of the material graspingly compressing the material between the dies, without rupture or injury thereto in the process 20 of forming and separating the dies and material in an analogous manner for a free withdrawal of the finished product.

Another object of the invention is to provide 25 opposing dies arranged in two series, with the dies of each series coupled and supported to travel as endless carriers, and as carriers adapted to intersect each other for bringing the dies progressively into overlapping degrees to positions of intermesh 30 and adjacent registry in a corresponding direction of motion with that of a traveling web for engaging the web between the dies, and coöperatively continue their travel in a tangential plane for a determined period 35 and under a lateral or clamping pressure for compressingly confining the material between the dies until it assumes a permanent set.

Another object of the invention is to provide 40 a series of die members of one class, arranged and supported to travel as an endless carrier and each relatively staggered to the die of a second class of a series, and each die of said second class fulcrumed to 45 swing independently of its next adjacent die, and upon axes located diametric to the axes of the respective dies of the first class, whereby two adjacent dies of the second class as companions segmentally register and 50 coöperate with a respective die of the other class. In corrugating a web of material the

opposing dies operate alternately upon the opposite sides or surfaces of the web and progressively in a folding-like or embracing action converts the material to the shape of 60 the dies, whereby the material is not subjected to any wedging or stamping influences which rupture or weaken the finished product.

Further objects and features, as may relate to the details of construction and arrangement of parts, are more fully set forth in the description of the accompanying drawings which illustrate a preferred embodiment of the invention, and in such 65 drawings like characters of reference denote corresponding parts throughout the several views, of which:

Figure 1 is a side elevation partially illustrating the corrugating and punching machine primarily showing the transmission to the various driven parts. Fig. 2 is a perspective view showing the work accomplished by the corrugating mechanism of a preferred form. Fig. 3 is a partial longitudinal 75 section of the corrugating or fluting devices. Fig. 4 is an enlarged end elevation of a section of the upper endless carrier and former dies. Fig. 5 is an enlarged bottom plan view partially in section showing a 80 portion of the lower endless carrier and former dies. Fig. 6 is an enlarged section on line 6—6, Fig. 3. Fig. 7 is an enlarged section on line 7—7, Fig. 3.

As illustrated, the machine is adapted to 90 operate upon a web of paper for printing, perforating and corrugating the same for manufacturing egg carriers in a continuous performance. The invention herein, however, is more principally directed to the 95 means for corrugating or fluting the paper or card-board and therefore will be treated as separate from a complete organized machine.

The printing devices may be of any well-known type of construction operating upon a web of paper and driven at a proper ratio with respect to the perforating or punching devices and corrugating devices in order to properly feed the paper to the corrugating 100 devices.

Referring to Fig. 1 of the drawings, 1 indicates a web of paper or card-board suitably journaled by means of a spindle 2 supported in bracket extensions 3, projecting 110 from the main side frame 4 of the machine. The paper is fed between a pair of rolls 5, 6,

suitably supported and journaled, from whence it is fed to the rotary printing mechanism for printing upon either one or both of the sides of the strip. The printing mechanism may be of any well-known form.

From the printing mechanism the strip passes between perforator devices comprising a reciprocating die carrier 7 slidably mounted upon the side frames of the machine. The die carrier supports a reciprocating punch carrying head 8. The punching mechanism is reciprocated longitudinally with the feed of the paper and at a ratio during a perforating operation equal to the rate of paper feed, so as not to interfere with the feed of the paper, or injure the paper during the co-operation of the punch and die members.

The punching mechanism is reciprocated in proper time movements coördinately to a preferred operation preferably by the following devices:

9 indicates the main driving shaft receiving its rotation and power from any suitable source. A pinion 10 is fixed to this shaft meshing with a gear 11 fixed upon a shaft 12, said shaft being suitably journaled in the side frame 4. The shaft 12 has a gear 13 fixed thereon in mesh with a gear 14 fixed on a shaft 15 journaled in the side frames. Said gear 14 connects with a train of gears leading to the printing cylinders. The shaft 15 is provided with a cam 16 adapted in its rotation to engage the lever 17 suitably fulcrumed upon the side frame. This lever 17 connects with an extensible connecting rod 18 and said rod connects with the die carrier 7. Thus the cam 16 in each cycle will rock the lever 17 to reciprocate the punching mechanism.

19 indicates a spring connecting with the lever 17 for yieldingly urging the lever against the cam. A second cam 20 is fixed upon the shaft 15 coöperating with a lever 21 suitably fulcrumed in the side frame of the machine. Said lever at its fulcrum end is provided with a crank disk 22, which pivotally connects with an extensible pitman 23, said pitman in turn connecting with the vertically reciprocating punch head 8. Thus, whenever the lever 21 is rocked, it will impart motion to the crank disk and pitman for operating the punch carrying head 8.

From the punching mechanism the paper passes between coating feed rolls 24, 25, for feeding the strip to the corrugating fluting mechanism. These feed rolls have their peripheries frictionally engaged and positively rotated, and in driving connection with the transmission of the machine. The shaft 15 has a bevel gear 26 fixed thereon meshing with a bevel gear 27 fixed upon a shaft 28. Said shaft 28 is supported and journaled in the bracket bearings 29-29, connected to the side frame 4. The shaft 28 extends rear-

wardly to the corrugating or fluting mechanism. The opposite end of the shaft is provided with a bevel gear 30 in mesh with a bevel gear 31 fixed upon a shaft 32 suitably journaled in the side frames of the machine, 70 and the shaft 32 has a gear 33 fixed thereon, in mesh with a gear 34 fixed upon a shaft 35, the shaft 35 being journaled in the side frames of the machine.

The gear 34 is in mesh with a gear 36 and 75 the gear 36 connects in train with the gears 37, 38. The feed rollers 24, 25 each have their shafts suitably journaled in slide blocks, sliding within guide brackets or bearings 39, supported upon the side frames. 80

Corrugating or fluting devices.

In the manufacture of corrugated or fluted card-board it is desirable in the finished product that each corrugation be molded or 85 formed to a permanent set and without rupture or injury to the paper stock in the process of forming. The paper stock usually is in a tempered or treated condition as it is operated upon by the forming mechanism, 90 and thus is of a delicate texture and easily ruptured or injured if subjected to any undue pulling or stretching strains in forming each corrugation.

Corrugated paper board as largely used for 95 packing has the corrugations usually uniform and of small radius so that the rupture in the paper stock is not as perceptible or detrimental to effect its commercial utility.

When the corrugations are of large proportion and join each other with an abrupt fold, as shown in Fig. 2, wherein the product represents a scalloped configuration in cross-section rupture of the material while forming must be avoided, for otherwise the 100 product would be unduly weakened at the fold. With the semi-circular sections adapted to swing upon each other at their juncture fold to form cylinder containers, and weakening or rupture of the paper stock at 110 such hinging points renders them easily torn apart, destroying the usefulness of the package. In operating upon preprinted stock, stretching of the material is detrimental to and mars the printing finish, and destroys 115 the article as a product of quality.

With my improvement the forming resolves itself into a process, progressively operating upon the stock in the direction of its feeding traverse longitudinally comparative 120 to a rolling motion so that the stock is not subjected to strain transverse and resisting to the feed. The opposing forming dies in their co-operation engage the paper in a feeding direction and in an alternate relation with respect to each other. That is to say, in forming a semi-circular corrugation the upper die draws the material in the direction of feeding traverse and in a sector proportion toward the die surface of a seg- 130

mental lower die; the engaged dies continuing in travel in a line of paper feed, and followed by companion segmental lower die moving to close toward the other, graspingly compressing the material in shape by drawing the material over the upper die completing a corrugation.

A series of upper and lower dies arranged in the form of endless carriers coöperating for a given length of travel compressing and confining the material to its molded form for subjecting the material to a setting period in the process and released from the dies when in a permanently set condition. The withdrawing operation is similar to the forming operation in that the dies separate or move apart progressively in the line of paper traverse so that the material is not subjected to withdrawing strains. The material as it is fed from the printing and perforating devices is guided over the roller 40 journaled between the side frames of the machine (see Fig. 3), from which it is fed to the forming dies. A feeding ratio between the forming mechanism and printing or perforating mechanism is established so that its traverse is relatively faster through the punching and printing mechanism than through the forming mechanism to accommodate for the variance in the lineal measurements of the material before and after forming. This difference in feed, loops the material to allow sufficient slack to the material between the forming and punching mechanism so that no pulling strains will be imparted as the material is drawn or formed over the coöperating upper and lower dies. The upper dies arranged as an endless carrier for shaping the material into the particular design illustrated comprise a series of rollers 41 in spaced relation and connected by links 42.

The arrangement for mounting, supporting and tracking the dies may be variously modified, but as disclosed, the upper dies are linked together in the form of an endless carrier, engaged over sprocket wheels at the ends of the carrier runs. The upper dies in their forward carrier run coöperating with the lower dies in a corresponding carrier run. The sprocket wheels are arranged in sets or pairs, although other forms of transmitting support are adaptable. As illustrated, the carrier transmitting supports are the duplicates of each other, each comprising a pair of sprocket wheels 43-43, fitted upon a shaft 44. The shaft at its ends is journaled in bearing blocks 45 each vertically adjustable in a bearing bracket 46 respectively horizontally adjustably secured to the side frames 47 of the machine. Each bearing bracket 46 is supported and secured upon its side frame between opposing set screws 48-48, engaged respectively with lugs projecting from the side frame.

This enables the bearing brackets to be horizontally adjusted for bringing the upper and lower dies into mesh or registry and controlling the tension of the die carrier runs.

The dies 41 axially have a stud 49 projecting from each end which connects with the links 42 forming endless chains at the opposite ends of the dies, and as the construction of each is the duplicate of the other and similar as to both of their opposite ends detail reference will be made in the singular.

The stud 49 is engaged through an enlarged bore of a collar or bushing 50 (see Figs. 4, 6 and 7) which loose union provides for a slight lateral play of the die axis independent of the chain or carrier.

An annular flange 51 is formed around the periphery of the bushing 50 as a division wall for the oppositely projecting links 42, and the bushing and links are held in place by a washer 52 and a screw 53 screw-threaded into the end of the stud.

Beneath the return run of the upper die carrier 1 provide a support or track 54 suitably supported upon the side frames of the machine and upon which the roller dies 41 travel to avoid any intermediate sagging of the carrier run, which would strain the sprocket wheel carrying shafts 44-44, or exert undue counter resistance to the transmitting motion of the carrier.

The lower dies comprise a plurality of die members 55, directly linked together to form an endless carrier, looping and engaging over sprocket wheels to provide forward and return runs, with the dies comprised in the forward run coöperating with roller dies comprised in the forward run of the upper carrier.

Each of the lower die members is the duplicate of the other, each having ears 56, 57 projected from their lower opposite edges, and preferably arranged at or toward the longitudinal die ends, with the ears in a staggered relation with respect to the ears projecting from a next adjacent die. The ears of each individual die at one edge are also in staggered relation with respect to the ears at the opposite edge in the particular design of die so that the dies are universal for assembling.

The ears of two adjacent dies fulcrum or swivel upon a pivot rod 58 with the axis of the rod as a fulcrum axis for the dies diametric with the adjoining die side faces. This abuts and parts two adjacent lower dies along a line diametric with the axis of a coöperating upper die, so that such two lower dies are adapted to segmentally, or in profile, register with such upper dies, each lower die in the instance herein having a die surface area of one half of the die or forming surface of its upper companion die. Each lower die therefore comprises two op-

posite half-die segments coacting with the die surfaces of two adjacent upper dies. In the process of forming the material into a corrugation at the receiving end of the carriers, assuming that the lower die *a*, Fig. 3, advanced to approximately its carrier run plane, and before the upper die *b* has advanced to the position shown, the material extends approximately in a straight line 10 from the upper surface of the lower die at its recess edge *c* to the guide roller 40. As the opposing upper and lower dies continue in their forward feeding direction the upper die *b* will tangentially engage the upper surface 15 of the material and in its rotary motion about the axis of shaft 44 roller-like lap the material over a portion of its periphery, and with its continued motion draw therewith the material beyond the upper die. The material 20 is thus initially shaped around the upper die, and as the upper advances into registry with the coöperating segmental die portion of the lower die *a* the material is compressed between said meshing die members, and thus retained throughout the run 25 length of said dies. The forming operation is completed by a successive lower die member *d* moving into registry with the upper die member *b* in a feeding direction, clasping, embracing and compressing the material over said upper die member. The upper and lower dies therefore successively and relatively alternately, and in a staggered relation, engage the material and thereby approximately 30 relieve the material from any lateral or wedging strains which have a tendency of tearing or rupturing the material.

It will be noticed that the progressive motion of one die over that of the other opposing die is the result of the difference in motion due to the angular velocity of the die when moving around the sprocket wheels. This enables one die to function or 45 transform the material before that of the next opposing die, so that there is no forcing of the material between two edge points. At the discharge or delivery end of the die carriers the dies separate and withdraw from 50 the formed material in a manner analogous to that when they move into registry, which provides a free withdrawal of the molded or formed material.

The hinge pivot rods 58 project beyond 55 the ends of the dies, as shown in Figs. 5, 6 and 7, to serve as a gudgeon for supporting the dies around the sprocket wheels and upon guides or bridge bars 59-59, 60-60, along the carrier runs. The lower dies as 60 a carrier similar to the upper dies is transmittingly engaged over sprocket wheels. The sprocket wheels engage with the projecting ends of the pivot rods 58. The projecting ends of the pivot rods 58 are each 65 provided with a sleeve roller 61, (see Fig. 5),

retained upon the rod by a screw 62 screw-threaded into the end of the rod. A pair of sprocket wheels 63-63, in spaced relation, and at the forward end of the carrier are fixed upon a shaft 35 journaled in bearings 70 64-64, respectively mounted upon the side frames of the machine. The sprocket wheels meshing with the rollers 61 respectively projecting from the opposite sides of the dies, and the shaft 35 constitute the prime mover 75 for transmitting the lower dies as a carrier, which in turn transmit motion, through the intermesh of the upper and lower dies, to the upper dies as a carrier. The shaft 35, as heretofore described, being rotated by 80 gear 34 fixed upon one end of said shaft. A second pair of sprocket wheels 63-63, at the opposite end of the lower die casing, respectively meshing with the rollers of the pivot rods 58, and fixed in a spaced relation 85 upon the shaft 65, journaled in the bearings 66-66, mounted upon the side frames.

To prevent sagging of the die carrier runs which would displace the lower dies of the forward carrier run, engaged with the die comprised in the forward run of the upper dies, I provide bridge bars 59-59 at the opposite end of the dies, upon which the rollers 61 travel, as shown in Figs. 3 and 7. The bars are suitably supported from and 95 mounted upon the side frame in any approved manner. The dies comprised in the return run of the lower die carrier are likewise supported by bridge bars 60-60, disposed at the opposite ends of the dies over 100 which their carrier rollers 61 travel to support the weight of the dies as a carrier and relieve the transmitting shaft of any carrier sagging strains.

The die carriers as a unit through their 105 journal bearings are mounted upon carriage supports 67-67, extending longitudinally with the carrier runs and tracked upon the side frames of the machine with the rear end of said supports connected as a unit and 110 provided with a depending arm 68 as a journal bracket for the hand wheel screw 69 having its screw shank end engaged with a cross-bar 70 as a web connected with the side frames. This provides means for longitudinally adjusting the die carriers toward and from the punching and printing machine, for lining up the machine for a proper relative registry of printing, punching and corrugations in the finished product. 115

After each corrugation has been initially formed, for some grades of stock, it is desirable to maintain the formed material under compression between the dies for a period allowing for a permanent set before 125 withdrawal. This I accomplish in providing tension means between the forward run of the upper die carrier engaging the dies, and, as shown, at their opposite axle or axis ends. 130

As a duplicate construction is followed for each end, the description will be confined to the singular and will comprise a rigid supporting bar 71 suitably supported 5 and extending longitudinally with the carrier runs. A series of screw ferrules 72 in a spaced relation engage through the bar 71, each slidably supporting a plunger rod 73 connecting to and dependently yieldingly 10 supporting a shoe 74 extending longitudinally with the carrier run. The shoe engages against the links of the carrier chain coupling the upper dies, a coil spring encircles the plunger engaged between the end 15 of the ferrule and shoe for exerting a downward pressure upon the shoe compressingly maintaining the upper dies in their intermesh with the lower dies in their forward carrier runs. The ends of the shoes are flared 20 to provide guides over the chain links. Any number of spring actuated plungers may be employed, depending upon the length of the carrier runs or as may be required for applying and maintaining the dies under 25 compression under constant or varying degrees for a given length of travel.

At the discharge or withdrawal end of the carrier, the finished product travels over a table 75 located at a proper elevation with 30 respect to the lower dies for a free separation of the dies from the corrugations of the finished product.

The dies or forming mechanism may be inclosed in a casing 76 for forming the material within a chamber for hygrometric purposes or material treatment beneficial to forming or shaping the material or in molding the same, and as any process for material treatment other than that resulting from the functioning or operation of the elements of the mechanical combination, may be treated as separate and apart thereof, no specific mention thereof is made herein.

45 The relative number and arrangement of either upper and lower dies comprised in a carrier series may be variously modified and the upper carrier may be in the proportions of a wheel instead of that of an endless 50 chain, depending chiefly upon the degree of corrugation desired and the use for which the product is intended. The configuration of the dies may be variously modified to present any form appropriate for the result 55 to be obtained, and the driving effected in any convenient manner.

Having described my invention, I claim:—
1. In a device of the class described, an endless carrier comprising a series of dies of one 60 class in a spaced relation, a second endless carrier comprising a series of dies of a second class independently fulcrumed with respect to each other, and arranged with the die surfaces of adjacent dies mating with a respective die of the first class, said carriers hav-

ing adjacent forward carrier runs bringing the dies of both classes into coöperation, progressively intersecting each in a staggered and mating relation compressing a traveling web of material to form therebetween, 70 and correspondingly separating said dies, and means for longitudinally adjusting the dies of the first class as a carrier unit for alining its dies with the dies of the second class.

2. In a device of the class described, an endless chain carrier, a series of dies of one class in spaced relation, each loosely journaled upon and between said carriers, a second endless carrier comprising a series of 80 dies of a second class, each independently swiveled from its next adjacent dies and segmentally mating with two adjacent dies of the first class, adapting said dies to mate and interlock in a staggered relation in a 85 coöperating line of carrier travel, means for bridgingly supporting said dies of the second class along their carrier runs, and means for yieldingly maintaining said dies in their interlocked arrangement along their coöperative line of travel.

3. In a device of the class described, an endless chain carrier, chain transmitting wheels for supporting said carrier, a series of dies of one class in spaced relation carried by and swiveled upon said carrier, a series of dies of a second class fulcrumed upon one another to form an endless carrier and adapted to swing together and apart as the dies relatively approach and depart from a 100 line of coöperation with the dies of the first class, the dies of both classes relatively arranged for bringing them alternately into line of coöperation whereby the material to be formed is progressively engaged between 105 said dies and the relative dies of both classes alternately brought into and out of their mating relationship.

4. In a device of the class described, an endless chain carrier, chain transmitting 110 wheels for supporting said carrier, a series of dies of one class in spaced relation carried by and swiveled upon said carrier, a series of dies of a second class fulcrumed upon one another to form an endless carrier 115 and adapted to swing together and apart as the dies relatively approach and depart from a line of coöperation with the dies of the first class, the dies of both classes relatively arranged for bringing them alternately into line of coöperation, said dies of the second class each arranged to segmentally mate with and interveningly between two adjacent respective dies of the first class, whereby the material to be formed is 125 progressively engaged between said dies and the relative dies of both classes alternately brought into and out of their mating relationship.

5. In a device of the class described, an 130

endless chain carrier, chain transmitting wheels for supporting said carrier, a series of dies of one class in spaced relation carried by and swiveled upon said carrier, a series 5 of dies of a second class fulcrumed upon one another to form an endless carrier and adapted to swing together and apart as the dies relatively approach and depart from a line of coöperation with the dies of the first 10 class, the dies of both classes relatively arranged for bringing them alternately into line of coöperation, said dies of the second class each arranged to segmentally mate with and interveningly between two adjacent 15 cent respective dies of the first class, where-

by the material to be formed is progressively engaged between said dies and the relative dies of both classes alternately brought into and out of their mating relationship, and means for supporting and compressibly maintaining said dies together during the co-operative line of travel. 20

In witness whereof, I hereunto subscribe my name, as attested by the two subscribing witnesses.

JOHN N. QUINN.
